US00D932634S

(12) **United States Design Patent** (10) Patent No.: **US D932,634 S**
Kawakami et al. (45) Date of Patent: **** Oct. 5, 2021**

(54) **MEDICAL PATCH**

(71) Applicant: **TEIKOKU SEIYAKU CO., LTD.**,
Kagawa (JP)

(72) Inventors: **Satoshi Kawakami**, Higashikagawa
(JP); **Kunihiro Matsushita**,
Higashikagawa (JP)

(73) Assignee: **Teikoku Seiyaku Co., Ltd.**,
Higashikagawa (JP)

(**) Term: **15 Years**

(21) Appl. No.: **35/509,300**

(22) Filed: **Nov. 5, 2019**

(80) **Hague Agreement Data**

Int. Filing Date: **Nov. 5, 2019**

Int. Reg. No.: **DM/207129**

Int. Reg. Date: **Nov. 5, 2019**

Int. Reg. Pub. Date: **May 8, 2020**

(30) **Foreign Application Priority Data**

May 7, 2019 (JP) 2019-009791
May 7, 2019 (JP) 2019-009793

(51) **LOC (13) Cl.** **24-02**

(52) **U.S. Cl.**

USPC **D24/189**

(57) **CLAIM**

The ornamental design for medical patch, as shown and described.

DESCRIPTION

The patent or application file contains at least one drawing executed in color. Copies of this patent or patent application publication with color drawing(s) will be provided by the Office upon request and payment of the necessary fee.

1.-2. Medical patch

1.1 : Perspective

1.2 : Front

1.3 : Back

1.4 : Left

1.5 : Right

1.6 : Top

1.7 : Exploded

2.1 : Perspective

2.2 : Front

2.3 : Back

2.4 : Left

2.5 : Right

2.6 : Top

2.7 : Exploded

(Continued)

Each medical patch has one center medicine sheet, and two rectangular transparent release sheets. The bottom view is a mirror image of the top view.

1 Claim, 14 Drawing Sheets
(14 of 14 Drawing Sheet(s) Filed in Color)
